(57) **CLAIM**

The ornamental design of a protective padding for martial arts training, as shown and described.

DESCRIPTION

FIG. 1 is an assembled perspective view of a protective padding for martial arts training

FIG. 2 is a front elevation view of the protective padding for martial arts training

FIG. 3 is a back elevation view of the protective padding for martial arts training

FIG. 4 is a left side elevation view of the protective padding for martial arts training

FIG. 5 is a right side elevation view of the protective padding for martial arts training

FIG. 6 is a top plan view of the protective padding for martial arts training; and,

FIG. 7 is a bottom plan view of the protective padding for martial arts training.

The broken lines in FIG. 3 define boundaries of the claimed design and form no part of the claimed design.
